UNITED STATES PATENT OFFICE.

FRANK C. DORMENT, OF WELLINGTON, OHIO, ASSIGNOR OF ONE-HALF TO ALBERT T. FLETCHER, OF WASHINGTON, DISTRICT OF COLUMBIA.

VAPORIZING INHALER.

Application filed October 29, 1925. Serial No. 65,537.

This invention relates to a vaporizing inhaler for use in the prevention and treatment of certain diseases of the respiratory organs. One of the objects of the invention 5 is to provide a simple and inexpensive device by means of which any medicated solution (oil or aqueous) can be converted into a fine vapor suitable for inhalation and containing all the ingredients of the solution. A further object is to provide an instrument by 10 means of which the vaporizing of the liquid may be effected by the simple act of inhalation or breathing through the nose or mouth without the danger of any portion or part 15 of said solution reaching the nose or throat except in a highly subdivided vaporous or gaseous form.

Further objects of the invention are to 20 provide a vaporizing inhaler of the character referred to which is small, compact and easy to sterilize and to use, which has no movable or adjustable parts liable to get out of order and which can be manufactured at a very low cost.

25 A further object of the invention is to provide a device in which a minimum quantity of the medicine is used and in which a greater proportion of that used actually reaches the portions of the respiratory tract 30 needing treatment.

A further object is to provide a device by 35 which a suitable medicant may be applied to the mucous membranes in actual substance and in such a manner that the delicate tissue will not be irritated.

With the above and other objects in view 40 the invention may be said to comprise the instrument as illustrated in the accompanying drawings hereinafter described and particularly set forth in the appended claim 45 together with such variations and modifications thereof as will be apparent to one skilled in the art to which the invention appertains.

Reference should be had to the accompanying drawings forming a part of this 50 specification in which Fig. 1 is a vertical section showing an instrument embodying the invention placed in an ordinary glass tumbler which serves as a receptacle for the liquid to be vaporized by the act of inhalation; Fig. 2 is a section taken on line 2—2 55 of Fig. 1; Fig. 3 is a section taken on line 3—3 of Fig. 1; Fig. 4 is a side elevation partially in section showing a modified form

of the invention; Fig. 5 is a section on line 5—5 of Fig. 4.

As shown in Figs. 1, 2 and 3 the vaporizing inhaler forming the subject matter of the present invention is preferably formed 60 of glass tubing and has a tubular body portion 1 open at the lower end and provided with an outwardly flaring base portion 2 forming a stable support for the instrument when it is stood on end. Around the base 65 portion 2 there are circumferentially spaced shallow indentations 3 through which air and liquid may pass into the interior of the hollow body. The upper end of the hollow body portion 1 is somewhat enlarged to provide 70 an expansion chamber 4, and extending upwardly from the upper end of the body 1 there is a tubular extension 5 which is of a diameter considerably less than the diameter of the tubular portion 1. The upper 75 and lower portions 6 and 7 of the tubular extension 5 are substantially in axial alignment with tubular body portion 1, and intermediate the portions 6 and 7 the tube 5 is bent laterally at 8 to provide a tortuous 80 passage for the vapor drawn upwardly from the body portion 1. The upper end of the tubular extension 5 has an enlargement 9 forming an expansion chamber and at the top of the enlarged portion 9 there is a relatively small outlet 10 through which the vapors may be drawn into the nose or mouth of the person using the instrument. At its lower end the tubular extension 5 has a portion 11 extending down into the expansion 90 chamber 4 at the upper end of the body portion 1 for a purpose to be hereinafter explained.

When the inhaler is used it is placed in a suitable receptacle with the base 2 resting 95 upon the bottom of the receptacle and a small quantity of the liquid to be vaporized and inhaled is placed in the receptacle. The person taking the treatment will place the mouth or nose to the outlet 10 of the 100 inhaler and inhale through the vaporizer. The reduction of pressure within the tubular body 1 will cause the liquid in the bottom of the container to flow through the openings 3 into the interior of the tubular 105 body 1 until practically all of the liquid in the container is within the base portion 2 of the inhaler. At the same time air will be flowing rapidly through the openings 3 and this air will violently agitate the small 110

body of liquid within the base 2 of the inhaler, and in passing through the violently agitated body of liquid, will become saturated with the vapor of the liquid and will carry along with it small drops of liquid. It is desirable that the air drawn into the respiratory tract contain the liquid only in a very minutely subdivided form and the vaporizer is so constructed that the larger drops of liquid will be deposited upon the walls thereof and only very minute particles of liquid can pass with the air through the outlet nozzle 10. The air in passing upwardly through the tubular body 1 passes into the expansion chamber 4 where the velocity is slowed down and larger particles of liquid carried in the air stream will be thrown against the wall of the body or against the outer wall of the portion 11 of the discharge tube which extends down into the expansion chamber 4. While passing through the bent portion 8 of the tube 5, any of the larger particles of liquid will be dashed against the walls of the tube and in passing through the expansion chamber 9, the velocity will be again slowed down and any of the larger particles of liquid which have been carried up in the air stream will be deposited upon the walls of the chamber 9.

The inhaler as shown herein is designed to be used with an ordinary glass tumbler and the height of the body portion 1 is such that when the inhaler is placed in the tumbler the top of the body portion 1 will be but slightly above the top of the tumbler. This enables the person using the inhaler to grasp the top of the tumbler with the tube 5 extending between two fingers which rest upon the top of the expansion chamber 4 and hold the body portion 1 with the base 2 thereof tightly against the bottom of the tumbler. With a standard tumbler the amount of liquid used is preferably about one dram which is just about sufficient to fill the bottom of the tumbler to a point slightly above the top of the inlet

openings 3. As shown herein the inlet openings 3 are placed one diametrically opposite the other so that the air currents tend to force the liquid to the center and the liquid so forced inwardly will be continually falling back into the air stream so that a very effective mixing action is obtained and the air will become thoroughly saturated with vapor.

In modifications shown in Figs. 4 and 5 the inhaler has a tubular body 1^a, flaring base 2^a and inlet openings 3^a identical with the modification first described. The tube 5^a, however, opens directly into the upper end of the body portion 1^a the extension 11 being omitted. Otherwise the modified form shown in Figs. 4 and 5 is identical with that shown in Figs. 1, 2 and 3.

Having described my invention what I claim is:

A vaporizing inhaler comprising a tubular body portion having an open outwardly flared lower end portion adapted to rest upon the bottom of a container in which there is a small quantity of liquid the lower edge of said body portion having circumferentially spaced indentations forming passages permitting air and liquid to flow along the bottom of the container to the interior of the body portion, said body portion having an enlargement at its upper end forming an expansion chamber, and a tube of a diameter relatively small with respect to the body portion connected to the enlarged upper end of the body portion, said tube having a restricted discharge opening and an enlarged portion forming an expansion chamber adjacent the discharge opening, the discharge opening and enlargement being substantially vertically above said body portion, said tube being laterally bent between its enlarged portion and the body portion, to thereby form a tortuous baffle passage.

In testimony whereof, I hereunto affix my signature.

FRANK C. DORMENT.
